United States Patent Office

Des. 196,299
Patented Sept. 17, 1963

196,299

PORTABLE PRAYER BENCH OR THE LIKE

Lawrence E. Tedder, 4519 Rosemont Drive,
Little Rock, Ark.

Filed July 18, 1962, Ser. No. 70,973

Term of patent 14 years

(Cl. D15—8)

FIG. 1

FIG. 2

FIG. 4

FIG. 5

FIG. 6

I claim:

The ornamental design for a portable prayer bench or the like, as shown and described.
